INVENTOR

BY Victor J. Evans

ATTORNEY

WITNESS:

R. E. T. Inc.

UNITED STATES PATENT OFFICE.

JOSEPH S. MATTA, OF DETROIT, MICHIGAN.

FOUNTAIN SCRUBBRUSH.

Application filed June 9, 1924. Serial No. 718,924.

To all whom it may concern:

Be it known that I, JOSEPH S. MATTA, a citizen of the United States, residing at Detroit, in the county of Wayne and State 5 of Michigan, have invented new and useful Improvements in Fountain Scrubbrushes, of which the following is a specification.

The object of my said invention is the provision of a fountain scrub brush that is, 10 simple and inexpensive in construction, susceptible of ready assembly and easy manipulation, and highly efficient in operation.

To the attainment of the foregoing, the invention consists in the improvement as 15 hereinafter described, and definitely claimed.

In the accompanying drawings, forming part of this specification:

Figure 1 is a perspective of the preferred 20 embodiment of my invention.

Figure 2 is a detail perspective showing a different arrangement of handle relative to the brush head.

Figure 3 is an enlarged longitudinal section through the brush head and its appurtenances.

Figure 4 is an enlarged detail section showing the cut-off valve.

Figure 5 is a detail perspective section of 25 the brush as shown in Figure 1.

Figures 6 and 7 are enlarged details of parts hereinafter explicitly referred to.

Similar numerals of references designate 30 corresponding parts in all of the figures of the drawings.

Among other elements my novel fountain 35 scrub brush comprises a head 1, preferably of wood, and of the general rectangular configuration illustrated. The said head 1 is equipped adjacent to one end with a keeper strap 2, and is provided at its upper side with a protuberance 3. At its underside, the said head 1 is provided with a longitudinal groove 4, and extending from 40 the said groove 4 is a chamber 5 in vertical alignment with the center of the protuberance 3. It will also be noticed that the head 1 is provided at its underside with two groups of bristles 5 arranged at opposite 45 sides of the longitudinal center of the head.

In addition to the head 1 equipped as described, the brush comprises a longitudinal tube 6 closed at its ends and provided in its under-portion with apertures 7. The 50 said tube 6 is snugly seated in the before-

mentioned groove 4, and is provided with an upstanding arm 8 which rests in the chamber 5 and is provided with a diagonal threaded aperture 9 and is also provided with a horizontally disposed threaded aperture 10. The aperture 9 is for the engagement of an inclined pipe section 11 which extends to the rear side of the head 1. The horizontal aperture 10 is for the engagement of a threaded pipe section 12 which rests on the head 1. The handle of the brush is designated by 13 and is in the form of a pipe section, said pipe section being threaded at its forward end and adapted to be secured in the arm 11, or in the pipe section 12, according to the arrangement of the handle relative to the head 1. When the handle 13 is arranged as shown in Figure 1, the outer end of the pipe section 12 will be closed by plug 14, and when the handle 15 is arranged as shown in Figure 2, the outer end of the pipe section 11 will be closed by the same plug 14, arranged as appears in Figure 2. It will also be noticed by reference to Figure 2, that with the handle arranged as illustrated in Figure 2, the handle will be disposed under the strap 2 so as to take undue strain off the connection of pipe section 12 to the handle 13.

At a convenient point, preferably its rear end, the handle 13 is provided with a cut-off valve 15, and the casing of the said valve 15 may be, and preferably is, coupled at 16 to a hose 17 in connection with a source of water supply designated by 18.

It will be apparent from the foregoing that the parts of my novel brush are susceptible of being readily assembled, and that but little effort is necessary to change the handle 13 from the relation as shown in Figure 1 to that shown in Figure 2 and vice versa.

Manifestly in the arrangement as shown in Figure 1 the brush is adapted for general scrubbing purposes, and when the handle 13 is arranged as shown in Figure 2, the brush is adapted for efficient manipulation in narrow places.

Notwithstanding its practical advantages as hereinbefore set forth, my novel brush is simple and inexpensive in construction, and is strong and durable, and therefore well adapted to withstand the usage to which scrub brushes are ordinarily subjected.

Having described my invention, what I

claim and desire to secure by Letters-Patent, is:—

1. A hydraulic scrub brush comprising a head having a longitudinal central groove in its underside, and a protuberance at its upper side and also having a central chamber extending between said groove and the interior of said protuberance, bristles carried by said head and extending from the lower side thereof, a strap on the head adjacent to one end thereof; a tube arranged in the groove of the head and closed at its ends and having apertures in its lower portion, a tubular arm fixed to, and extending upwardly from said tube and having an inclined threaded aperture at an intermediate point in its height and also having a horizontally disposed threaded aperture adjacent to its upper end, a tubular threaded

handle for use in said apertures alternately, and a closure plug for use in said apertures alternately.

2. In a fountain scrub brush, the combination of a head, bristles carried thereby, a strap on said head adjacent to one end thereof, a conduit arranged in said head and having an up-right arm with inclined and horizontally disposed threaded apertures, pipe sections in threaded engagement with said apertures, and a threaded tubular handle for connection with said pipe sections alternately, said handle also adapted to be arranged under said strap, and a closure plug for closing the said ends of the pipe sections alternately.

In testimony whereof I affix my signature.

JOSEPH S. MATTA.
